UNITED STATES PATENT OFFICE

2,086,819

HEAT MOTOR

Lawrence M. Persons, Des Moines, Iowa, assignor
to Penn Electric Switch Co., Des Moines, Iowa,
a corporation of Iowa

Application September 21, 1934, Serial No. 744,934

6 Claims. (Cl. 60—25)

An object of my present invention is to provide an improved type of heat motor or that type of motor wherein a liquid is vaporized by an electric resistance element or other heating means 5 to expand a bellows or the like, the bellows being operatively connected with some member such as a valve disc to automatically control the operation thereof in accordance with the energization of the heating means, the device being comparatively simple to manufacture.

A further object is to provide a heat motor which can operate much quicker than the ordinary type, my heat motor having inherent structural features for accomplishing this purpose.

More particularly it is my object to provide a heat motor comprising a boiler and an expandable member having novel operating characteristics caused by a cup-like baffle wall within the boiler of the heat motor, a riser tube for returning liquid from the expandable member to the boiler and means to insure that liquid will leave the boiler from the lower portion thereof and return through the riser tube.

Still a further object is to so connect the controller member with a valve disc or the like to be controlled that lost motion is permissible to allow fluctuations of the controller member caused by the peculiar operating characteristics of my heat motor without actuating the valve disc except when the heating means for the boiler is de-energized.

With these and other objects in view my invention consists in the construction, arrangement and combination of the various parts of my device whereby the objects contemplated are attained, as hereinafter more fully set forth, pointed out in my claims and illustrated in the accompanying drawing, in which:

Figure 1 is a vertical sectional view through a heat motor embodying my invention and showing it connected with a valve, such as the type used for controlling the flow of gas to a gas burner.

Figure 1a shows a slight modification of Figure 1.

Figure 2 is a diagrammatic view of my invention showing it in the normally inoperative position.

Figure 3 is a similar diagrammatic view showing the heat motor in energized and actuating position.

Figure 4 is a similar diagrammatic view showing the return from the position of Figure 3 to the position of Figure 2 when the heat motor is de-energized.

Figure 5 is a diagrammatic sectional view on the line 5—5 of Figure 1; and

Figure 6 is a diagrammatic view on the line 6—6 of Figure 5.

On the accompanying drawing I have used the reference numeral 10 to indicate a bellows, by way of illustration, as an expandible pressure operated control member. The bellows 10 may be provided with a perforated ear 12 or the like for connection with some member to be controlled, as will hereinafter be described. The bellows 10 preferably has its lower end sealed relative to a base 14 and its other end sealed by a head 15 from which the ear 12 extends.

A boiler 16 is mounted on the base 14 and has a resistance wire 18 wound thereon for the purpose of heating the boiler when the resistance wire is energized. In place of resistance wire, any suitable heating means may be used. Within the boiler 16 I provide a baffle member 20 which is preferably cup shaped as shown in cross section in Figure 1.

Means of communication is afforded between the compartment within the bellows 10 and the boiler 16 in the following described manner:—A passageway 36 communicates with a valve seat 34 and with a passageway 22 extending to a check valve 24. The check valve 24 is normally seated by gravity against a seat 26. The seat 26 communicates by means of a passageway 28 with the bottom of the boiler 16.

A riser tube 30 is mounted in the base 14 and communicates by means of a passageway 31 with a second check valve 32 normally seated by gravity on the seat 34.

A housing 37 is mounted on the base 14 to enclose the bellows and the boiler. Extending through a slot 38 in one side thereof is an arm 40 pivoted on a pin 42. By means of a link 44 the arm 40 is operatively connected with the ear 12 whereby movements of the bellows 10 swing the arm 40 for the purpose of controlling any desired apparatus.

Another device is also illustrated as being controlled by the bellows and it will now be described: (The device mentioned is omitted from the diagrammatic showings in Figure 2, 3, and 4.)

A pin 46 depends from the bellows head 15 and is slidably mounted in a sleeve 48 extending upwardly from the base 14. The sleeve 48 is provided with a guide opening 50 and the pin 46 may be secured, as by a screw 52, with the head of the bellows to seal the pin 46 against 55

the escape of liquid within the bellows. I provide a second bellows 54 having a head 55 sealed relative to the head 15 and having its lower end sealed to the base.

5 A sleeve 56 surrounds the pin 46 and a return spring 57 is interposed between the upper end of this sleeve and the top of the sleeve 48 for the purpose of normally constraining the bellows 10 toward collapsed position. A washer 59 is held 10 assembled on the pin 46 by a stud-like element 14 and has ears 58 extending from opposite sides thereof. The ears 58 are connected by two pairs of springs 60 and 60a with snap acting yokes 62. The yokes 62 are provided with sharpened ends 15 64 oscillatable in notches 65 of brackets 66.

A valve device 68 is provided and normally seated against a valve seat 70 of a valve 72. The disc 68 has a socket-like sleeve 76 to slidably receive the element 74, a spring 78 being interposed between the two for normally constraining the element 74 upwardly relative to the disc 68. Projections 80 and 82 are provided on the valve disc 68 between which the yokes 62 operate.

Practical operation

25 The elementary operation of the present day heat motor involves the operation of a bellows or the like by the depression of a liquid in a boiler by heating and thereby boiling part of that liquid with an electric heater wound round the boiler. The bellows remains in operative position as long as heat is applied. The large size of the heater required to boil the liquid and thereby operate the bellows from a cold start in a reasonable length of time causes the boiler to be heated to an excessively high temperature. If the heater is maintained energized, the bellows remains in the expanded position. This accumulates heat which must be dissipated after the 35 heater is deenergized before the bellows can contract to its original position. The time required for heat dissipation causes a slow return of the bellows and when the bellows is connected with a gas valve of a furnace, for instance, the slow 40 return is objectionable. Also the opening operation of the gas valve is slow as a large amount of the liquid in the boiler must be heated before 45 vaporization takes place.

The particular construction I illustrate overcomes such slow action causing the heat motor to complete a cycle of operation in less than a minute which is actually from fifteen to twenty times faster than the ordinary heat motor. It should here be mentioned that I employ suitable 55 liquid substantially filling the boiler 16 and the bellows 10 when in collapsed position, as illustrated in Figure 2.

In operation, when the heating element 18 is energized, it will commence to boil the liquid in the boiler 16 causing it to recede from the position in Figure 2 and the bellows 10 to consequently expand. The baffle wall 20 will act to prevent convection currents from stirring the liquid in the boiler so as thus to speed up the initial vaporization of the liquid. It will be obvious that instead of one baffle wall several may be used to further increase the convection current prevention, if desired.

As the surface of the liquid recedes from the baffle wall 20 the liquid trapped therein will be boiled more violently due to its small thermal capacity and will hence vaporize much quicker than otherwise. This rapidly increases the recession of the liquid from the boiler and consequently the pressure, thus causing the greater

portion of the liquid to be depressed to the bottom of the boiler as shown in Figure 3 in a minimum of time, thus giving a quick expansion of the bellows 10.

As boiling of the liquid in the cup-like baffle 5 wall or tray continues, condensation occurs on the comparatively cool surface of the liquid at the bottom of the boiler. This continues until the liquid is completely evaporated from the tray, whereupon further condensation on the surface 10 of the liquid causes a decrease in the pressure, whereupon the bellows 10 will start to contract due to the action of the spring 57.

The liquid in receding from the boiler will pass through the check valve 24 which will be opened 15 by the liquid as shown in Figure 3, and when recession stops this valve will close. When the liquid starts to return it opens the valve 32 so that the return is through the riser tube 30. A small quantity of the liquid will be delivered through 20 the tube 30 to the tray 20 wherein it becomes immediately vaporized because the heating element is still energized, thus again increasing the pressure and stopping the return flow of liquid. If the heating element is energized a sufficient 25 period of time this slight pumping process occurs at intervals of one or two minutes, thus keeping the liquid in the tray and the top of the boiler very close to the boiling point of the liquid. This limits the temperature near the top of the boiler 30 to substantially that of the boiling point of the liquid so that excessive heat is prevented and the objection of slow collapse of the bellows 10 is thus somewhat lessened.

When the heating element 18 is de-energized 35 the boiler quickly cools from a point substantially the boiling point of the liquid to a point allowing condensation of the liquid in the boiler sufficient to start a return of the bellows toward a collapsed position and liquid is immediately 40 delivered from the riser tube 30 to the tray 20. This liquid is comparatively cool since it has been within the bellows rather than within the boiler so that, being sprayed against the baffle 20 and the wall of the boiler 16, it hastens the 45 cooling thereof and consequently the condensing action, the tray spills over into the boiler proper and this also aids in a very rapid condensation of the liquid and the bellows practically snaps back to its initial position.

A baffle such as 20a (see Figure 1a), which is not cupped, will give partial results as at the start of the opening operation the action will be just as rapid but as the liquid recedes in the boiler, the heat supplied to the surface of the 55 boiler would be gradually less and less as this heat could only reach the liquid by traveling down the walls of the boiler. These walls are left cold by the receding liquid. Thus the boiling of the liquid in the tray supplies a means to 60 transfer the heat from the hottest part of the heater in the boiler at its top to the surface of the receding liquid.

From the foregoing it will be obvious that the tray 20 therefore speeds up the start of the 65 opening operation by preventing convection currents; speeds up the opening operation by providing vapor pressure from the hottest point in the boiler; speeds up the start of the closing operation by limiting the temperature at the top 70 of the boiler and speeds up the closing operation by providing a large area for condensation surface against which the returning liquid is discharged. In the latter capacity the baffle acts somewhat like a fin of a heat exchanger.

In the foregoing operation the action of the heat motor per se has been described. I have found my heat motor especially adaptable for gas valves and have provided the described construction for connecting the bellows 10 with the gas valve for purposes which will now appear.

As the pin 46 raises, caused by the expansion of the bellows 10 the inner ends of the springs 10 and 60a pass over center with respect to the notches 65 causing the yokes 62 to snap upwardly, thus leaving the projections 80 and striking the projections 82. This will open the valve with a snap action, the springs 60 and 60a tending, after over center position is reached, to swing the yokes 62 upwardly.

As the slight pumping action described in the action of the heat motor occurs after the gas valve has opened and while the heating element 18 is still energized, there will be a slight raising and lowering of the pin 46 but it will not travel far enough to move the springs 60 and 60a downwardly again past the center represented by the notches 65. Thus the yokes 62 will retain the valve disc 68 open without any fluctuation in its position until such time as the heating element 18 is de-energized for permitting the bellows 10 to quickly collapse and during the last portion of the collapsing movement cause the yokes 62 to again snap downwardly for closing the gas valve quickly.

Some changes may be made in the construction and arrangement of the parts of my device without departing from the real spirit and purpose of my invention and it is my intention to cover by my claims any modified forms of structure or use of mechanical equivalents which may be reasonably included within their scope.

I claim as my invention:

40 1. In a heat motor, a boiler, heating means therefor, an expansible controller member communicating therewith, liquid sealed within said boiler and said expansible member, means within said boiler to prevent convection currents of the portion of the liquid within the boiler when said heating means is in operation, means for returning liquid from the expansible member to the boiler while the heating means is in operation, said means for preventing convection currents, also preventing returning liquid from condensing the vapors to an extent causing collapse of the expansible controller member and comprising a receptacle within said boiler to receive returning liquid, said receptacle being in heat conducting relation with the wall of said boiler to revaporize any liquid returned to the receptacle.

2. In a heat motor, a boiler, heating means therefor surrounding said boiler, an expansible controller member communicating therewith, liquid sealed within said boiler and said expansible member, a baffle wall within said boiler and connected with the wall thereof to prevent convection currents in the portion of the liquid within the boiler when the heating means is maintained in operation to form vapor both to drive the liquid from the boiler and into said expansible member and to keep said liquid from re-

turning to said boiler, said baffle wall having a cupped portion and means for returning liquid from the expansible member into said portion after the heating means has been so maintained in operation for a period of time and is then 5 rendered inoperative for the purpose of allowing the liquid to return to the boiler.

3. In a heat motor, a boiler, heating means therefor, an expansible controller member communicating therewith, liquid sealed within said 10 boiler and said expansible member, the means of communication between said boiler and said expansible member including a riser tube in said boiler for liquid returned from the expansible controller member and means to catch the returned liquid, said last means being in heat conducting relation to the boiler whereby it is heated by said heating means therefor and thereby quickly revaporizes any liquid returning to the boiler while the heating means is in operation. 20

4. In a heat motor, a boiler, heating means for a wall of said boiler, an expansible controller member communicating therewith, liquid sealed within said boiler and said expansible member, the means of communication between said 25 boiler and said expansible member including a riser tube in said boiler and two-way mechanism allowing exit of liquid from the boiler only from the bottom of the boiler and entrance thereto only through said riser tube and a baffle within 30 said boiler and connected with said wall to prevent convection currents and increase the condensing surface of the boiler to facilitate condensation of the liquid returning through said 35 riser tube.

5. In a heat motor, a boiler, heating means therefor and surrounding said boiler, an expansible controller member communicating therewith, liquid sealed within said boiler and said expansible member, the means of communication between said boiler and said expansible member including a riser tube in said boiler and two-way mechanism allowing exit of liquid from the boiler only from the bottom of the boiler and entrance thereto only through said riser 40 tube and a baffle wall within said boiler and connected with the wall thereof to prevent convection currents and increase the condensing surface of the boiler to facilitate condensation of the liquid returning through said riser tube, said 45 baffle wall being cupped to retain a portion of the liquid within the boiler when the liquid recedes due to operation of said heating means. 50

6. In a heat motor, a boiler, heating means therefor and surrounding said boiler, an expansible controller member communicating therewith, liquid sealed within said boiler and said expansible member and a baffle wall within 60 said boiler and connected with the wall thereof to increase the condensing surface of the boiler to facilitate condensation of the liquid returning thereto when said heating means is not in operation, said baffle wall being cupped to retain a portion of the liquid within the boiler when 65 the liquid recedes due to operation of said heating means.

LAWRENCE M. PERSONS.
